partnership

Application September 20, 1949, Serial No. 5,095

Term of patent 7 years

(Cl. D45—19)

To all whom it may concern:

Be it known that I, Delmar E. Demaree, a citizen of the United States, residing at Kokomo, in the county of Howard and State of Indiana, have invented a new, original, and ornamental Design for a Combined Lapel Ornament and Flower Holder, of which the following is a specification, reference being had to the accompanying drawing, forming a part thereof.

Fig. 1 is a front elevational view of a combined lapel ornament and flower holder, embodying my new design;

Fig. 2 is a side elevational view thereof taken from the right side of Fig. 1;

Fig. 3 is a rear elevational view thereof; and

Fig. 4 is a transverse sectional view thereof taken substantially on the plane indicated by the line 4—4 of Fig. 1.

I claim:

The ornamental design for a combined lapel ornament and flower holder, as shown.

DELMAR E. DEMAREE.
